Filed Jan. 15, 1971, Ser. No. 106,939

Term of patent 14 years

Int. Cl. D28—03

U.S. Cl. D86—8

FIG. 1 is an exploded top plan view of a hair styling comb showing my new design.

FIG. 2 is a top plan view thereof partly assembled.

FIG. 3 is a top plan view thereof fully assembled.

FIG. 4 is a transverse section taken in the direction of arrows 4—4 of FIG. 3.

FIG. 5 is a side elevational view taken in the direction of arrows 5—5 of FIG. 3.

FIG. 6 is an end view taken in the direction of arrows 6—6 of FIG. 3.

FIG. 7 is a top plan view of a modified form of the design of FIG. 1 wherein the surface decoration extends to the chamfer of the hair styling comb.

FIG. 8 is a section taken in the direction of arrows 8—8 of FIG. 7.

The bottom plan view of the design shown in FIGS. 3 and 7 is substantially identical thereto.

I claim:

The ornamental design for a hair styling comb, as shown and described.
